COMBINED HOLE CUTTER AND SHARPENING
TOOL OR THE LIKE FOR REPAIRING SEWN-IN
BICYCLE TIRES

Philip Quartararo, 2309 Avenue Y, Brooklyn, N.Y.

Filed June 24, 1964, Ser. No. 80,566

Term of patent 3½ years

(Cl. D54—13)

FIG. 1 is an exploded side elevational view of a combined hole cutter and sharpening tool or the like for repairing sewn-in bicycle tires embodying my new design, the opposite side being similar;

FIG. 2 is an enlarged partial plan view, looking along line 2—2 in FIG. 1;

FIG. 3 is an enlarged partial plan view, looking along line 3—3 in FIG. 1;

FIG. 4 is an enlarged partial plan view, looking along line 4—4 in FIG. 1;

FIG. 5 is an enlarged partial plan view, looking along line 5—5 in FIG. 1;

FIG. 6 is an enlarged partial plan view, looking along line 6—6 in FIG. 1;

FIG. 7 is a partial elevational view of several of the assembled component parts of the combination;

FIG. 8 is an enlarged front elevational view thereof; and

FIG. 9 is an enlarged top plan view taken along line 9—9 in FIG. 8.

I claim:

The ornamental design for a combined hole cutter and sharpening tool or the like for repairing sewn-in bicycle tires, as shown.
